[57] **CLAIM**

The ornamental design for a draft control knob for a wood burning stove or the like, as shown and described.

DESCRIPTION

FIG. 1 is a front elevational view of a draft control knob showing my new design;

FIG. 2 is a top elevational view thereof; and

FIG. 3 is a perspective view thereof taken from above and to the right of FIG. 1.

The rear surface of the draft control knob is substantially planar and unornamented.
